ADVERTISING DEVICE

John W. Haley, Bristol, R. I., assignor to Perfection Sales Corporation of New England, Cranston, R. I., a corporation of Rhode Island

Application January 5, 1940, Serial No. 312,577

4 Claims. (Cl. 40—125)

My invention relates to improvements in advertising devices particularly in the sign portions thereof bearing the advertising indicia.

An object of my invention is to provide a transparent advertising member for use in advertising signs having a convex outer surface and a rear surface having the edge on the rearmost portion thereof, said rear surface having depressions of the shape of advertising insignia extending forwardly therein and coatings of coloring matter applied to the bottoms of said depressions defining said insignia. I have found that if the outer surface of such a member be made convex, particularly spherically convex, that when the sign is viewed from in front, the said advertising insignia characters are readable through the front face of the transparent member and appear refracted from substantially the outer convex surface of said transparent member in the same degree of convexity as said outer surface, so that substantially all of said indicia may be observed when viewed from substantially any direction in front of said base, more particularly if said outer convex surface be spherically convex. I have found in practice that such signs can be read at angles approaching 90° from the perpendicular to the plane of said member, thus increasing largely the visibility of such signs and the impression they make on anyone viewing them. The outer convex surface appears to refract the light rays in a greater degree than if a plane outer surface be employed, which refraction may be increased by concaving the inner surface of said transparent member. The ideal type of such a member is the meniscus concavo-convex lens with both the concave rear and the convex front surfaces being spherical when the angle of refraction and stereoptic effect may be increased and regulated in the desired degree, although it is obvious that any suitable type of outer convex surface may be employed and any suitable type of plane or concave inner surface may be employed.

A further feature of my invention resides in the fact that the depressions are preferably provided with certain parallel side walls thereof inclined in substantially a single direction and a supplemental coating of coloring matter of a different shade is applied to said inclined walls so that when the device is viewed from in front, said differently shaded side walls may provide a perspective shading effect.

I have also discovered that good results can be obtained if the transparent member hitherto described is mounted on an opaque surface of the

base and I have also discovered that pleasing effects involving substantially the same degrees of refraction to produce the illusion of convexedly transparent images on the outer surface of the transparent member may be produced if the transparent member is mounted on a translucent light diffusing surface on said base and a light source is mounted in rear of said light diffusing surface.

These and such other objects of my invention as may hereinafter appear will be best understood from a description of the accompanying drawings, which illustrate various embodiments thereof.

15 In the drawing, Fig. 1 is a front elevation of an advertising device constructed in accordance with my invention.

Fig. 2 is a vertical sectional view thereof taken along the line 2—2 of Fig. 1.

Fig. 3 is a rear elevational view of the transparent member of my invention provided with a translucent light diffusing surface attached thereto, and broken away for the purpose of illustrating the depressions extending forwardly in said transparent member from the rear surface thereof.

Fig. 4 is a cross sectional view of said transparent member taken along the line 4—4 of Fig. 3.

30 Fig. 5 is a front perspective view of an alternative embodiment of my invention wherein the base is provided with an opaque light reflecting surface on which the rear surface of said transparent member having the edge thereof on the rearmost portion thereof is mounted, said transparent member also being of concavo-convex meniscus shape.

Fig. 6 is a cross sectional view similar to Fig. 4 of the meniscus shaped transparent member employed in the embodiment of my invention shown in Fig. 5.

45 In the drawing, wherein like characters of reference indicate like parts throughout, 10 or 10' generally indicate embodiments of advertising devices constructed in accordance with my invention. In the description when referring to the parts of the embodiment shown in Figs. 1-4, I will employ unprimed reference characters, and when referring to similar parts in the embodiment shown in Figs. 5 and 6 I will employ primed reference characters. Said devices include the base 12 or 12' which base has a flat portion 14 or 14' thereof provided either with the translucent light diffusing surface 14 thereon as shown

in Figs. 1 and 2, or an opaque surface 14' as shown in Figs. 5 and 6.

My invention includes a transparent member 16 or 16' for use in advertising signs having a convex outer surface 18 or 18' and a rear surface 20 or 20' having the edge 22 or 22' thereof on the rearmost portion thereof. Said rear surface 20 or 20' is provided with the depressions 24 or 24' of the shape of advertising insignia 28 or 28' extending forwardly therein and a coating 26 or 26' of coloring matter applied to the bottoms of said depressions defining said insignia. Said transparent member 16 or 16' may be made of any suitable transparent material such as glass, transparent resin, Lucite, crystal, etc.

A main feature of my invention comprises this transparent sign member 16 or 16' having a convex outer surface 18 or 18' and a rear surface 20 or 20' having the edge 22 or 22' thereof on the rearmost portion thereof, with said rear surface provided with said depressions 24 or 24' and the coatings 26 or 26' of coloring matter applied to the bottoms of said depressions defining said insignia. I have discovered that if said outer surface of the transparent member be made of a convex shape, that when the transparent member 16 or 16' is viewed from in front, said advertising insignia provided by the coatings 26 or 26' of coloring matter at the bottoms of said depressions 24 or 24' will appear refracted as the advertising insignia 28 or 28' with a convex curvature similar in convexity to that of the convex outer surface 18 or 18' from substantially the outer convex surface 18 or 18' of said transparent member 16 or 16' so that substantially all of said advertising indicia may be observable when viewed from substantially any direction in front of said base as shown in Fig. 5. The coating 26 or 26' may consist of any suitable type of paint, lacquer, or other coloring material suitably colored by pigment or otherwise.

The rear surface 20 or 20' of said transparent member 16 or 16' may be plane as the rear surface 20 of the embodiment shown in Figs. 1-4. I have discovered that by making the outer surface convex that the angle of refraction is increased to make the advertising matter or indicia 28 or 28' appear refracted from the outer convex surface 18 or 18'. The angle of refraction, however, of the light rays and hence stereoptic effect may be further increased if the rear surface 20' is concaved in addition, as in the embodiment shown in Figs. 5 and 6.

In the preferred embodiments shown, the outer surface 18 or 18' is preferably spherically convex in both embodiments to provide a solid spherical sector of the type commonly known as a lens, although my invention may be employed on lenses, other than of true solid spherical sector shape. In the embodiment shown in Figs. 5 and 6 the rear surface 20' also comprises a partially spherical concavity, preferably with a different degree of curvature from that of the outer surface 18', the relative degrees of curvature and hence convexity and concavity of the respective surfaces 18' and 20' varying the refractory power and hence stereoptic effect of the transparent member 16 or 16'. The transparent member 16 or 16' is preferably mounted in any suitable manner in or on the base 12 or 12'. In the embodiment shown in Figs. 5 and 6, the base 12' is provided with an opaque portion 14' over and to which the transparent member is suitably mounted. In the embodiment shown in Figs. 1 and 2, the transparent member 16 is mounted

over a suitable translucent light diffusing surface 14 and an electric light bulb 30, or other suitable light source, is mounted in rear of the transparent member 16 and the translucent light diffusing sheet 14 to attract more attention.

In order that the light source may not be reflected and refracted directly through the transparent member the translucent light diffusing surface 14 is interposed between said light source 30 and transparent member 16. A suitable reflecting mirror 34 may be mounted in said container in rear of said light source to reflect and converge the rays thereof through said transparent member 16. In the embodiment shown in Figs. 1 and 2, the electric light source 30 is mounted on a suitable base 36 mounted on the lower wall of the container 32 and suitably lighted from a suitable source of electricity by power provided through the wires 38. In the embodiment shown, the edge 22 or 22' of the rear surface 20 or 20' of said transparent member 16 or 16' is mounted substantially in alignment with the edge of said portion 14 or 14', whether it comprises the transparent portion 14 heretofore referred to, as shown in Figs. 1-4, or the opaque portion 14' heretofore referred to as shown in Figs 5 and 6.

My invention provides satisfactory qualities, even if the light source and translucent light diffusing portion 14 be omitted and the translucent portion be replaced by a suitable opaque reflecting background 14', the advertising insignia being readily observable in convex shape as appearing from the outer convex surface 18' of said transparent member as shown in Fig. 5, the outside light, reflected by said opaque surface 14' and refracted through said transparent member 16' being sufficient to bring out the advertising insignia 28' in the desired fashion.

As stated, however, in the embodiment shown in Figs. 1-4 I produce substantially the same effect with an additional source of light behind it and the advertising effect is somewhat more startling.

A further feature of my invention comprises the increasing of the perspective effect produced by the advertising letters or insignia provided by the depressions 24 or 24' and the coloring matter 26 or 26' on the bottoms thereof. If the walls 40 or 40' of said depressions are not painted they may refract a silvery sheen to the edges of the advertising insignia.

I may, however, in accordance with my invention, provide certain parallel side walls 42 or 42' of said depressions inclined in substantially a single direction and if coatings of coloring matter 44 or 44' of a different shade from that of the coatings of coloring matter 26 or 26' in the bottom of said depressions be applied to said inclined side walls 42 or 42', said differently shaded inclined side walls of said advertising insignia in said depressions 24 or 24' will thus provide a perspective shading effect increasing the perspective effect and reality of the illusions of making said advertising insignia appear refracted from substantially the outer convex surface of said transparent member and provided, when so refracted, with an exaggerated perspective effect of depth as shown in Fig. 5.

For ease of mounting the transparent member 16 or 16' over the flat portion 14 or 14' of said gripping portion 12 or 12' it may be provided with the spring ring 50 or 50'.

It is apparent therefore that I have provided a novel type of startling advertising device con-

structed of a small number of simple parts which may be employed for displaying advertising matter in a startling and novel fashion to have it observable from substantially any angle in front thereof and a novel type of a transparent member for use as such an advertising sign with the advantages explained above.

It is understood that my invention is not limited to the specific embodiments shown and that various deviations may be made therefrom without departing from the spirit and scope of the appended claims.

What I claim is:

1. An advertising device, comprising, in combination, a base having a flat translucent light diffusing transparent member mounting surface and a transparent member having a convex outer surface and a rear surface having the edge thereof on the rearmost portion thereof, mounted on said base over said translucent light diffusing portion to have the edge thereof substantially in alignment with the edge of said portion, said rear surface having depressions of the shape of advertising insignia extending forwardly therein, said depressions having certain parallel side walls thereof only inclined in substantially a single direction, a coating of coloring matter applied to the bottoms of said depressions defining said insignia and a coating of coloring matter of a different shade applied to said inclined side walls and a light source mounted in rear of said translucent light diffusing portion, whereby all said advertising insignia may appear refracted from substantially the outer convex surface of said transparent member so that substantially all of said advertising indicia may be observable when viewed from substantially any direction in front of said base with said differently shaded inclined side walls thereof providing a perspective shading effect.

2. An advertising device, in combination, a base having a flat opaque light reflecting surface and transparent member having a convex outer surface and a rear surface having the edge thereof on the rearmost portion thereof, mounted on said base over said light reflecting surface, said rear surface having depressions of the shape of advertising insignia extending forwardly therein, and a coating of coloring matter applied to the bottoms of said depressions defining said insignia, whereby all said advertising insignia may appear refracted from

substantially the outer convex surface of said transparent member so that substantially all of said advertising indicia may be observable when viewed from substantially any direction in front of said base.

3. An advertising device comprising, in combination, a base having a flat transparent member mounting surface and a transparent member having a convex outer surface and a rear surface having the edge thereof on the rearmost portion thereof, mounted on said base portion, said rear surface having depressions of the shape of advertising insignia extending forwardly therein, said depressions having certain parallel side walls thereof only inclined in substantially a single direction, a coating of coloring matter applied to the bottoms of said depressions defining said insignia and a coating of coloring matter of a different shade applied to said inclined side walls, whereby all said advertising insignia may appear refracted from substantially the outer convex surface of said transparent member so that substantially all of said advertising indicia may be observable when viewed from substantially any direction in front of said base with said differently shaded inclined side walls thereof providing a perspective shading effect.

4. An advertising device comprising, in combination, a base having a flat opaque light reflecting surface and a transparent member having a convex outer surface and a rear surface having the edge thereof on the rearmost portion thereof, mounted on said base over said light reflecting surface, said rear surface having depressions of the shape of advertising insignia extending forwardly therein, said depressions having certain parallel side walls thereof only inclined in substantially a single direction, a coating of coloring matter applied to the bottoms of said depressions defining said insignia and a coating of coloring matter of a different shade applied to said inclined side walls, whereby all said advertising insignia may appear refracted from substantially the outer convex surface of said transparent member so that substantially all of said advertising indicia may be observable when viewed from substantially any direction in front of said base, with said differently shaded inclined side walls thereof providing a perspective shading effect.

JOHN W. HALEY.
